UNITED STATES PATENT OFFICE.

ROBERT L. JOHNSON, OF HANLEY, ENGLAND.

DESIGN FOR A CUP.

SPECIFICATION forming part of Design No. 36,330, dated May 19, 1903.

Application filed April 11, 1903. Serial No. 152,267. Term of patent 3½ years.

To all whom it may concern:

Be it known that I, ROBERT L. JOHNSON, a subject of the King of Great Britain, and a resident of Hanley, Staffordshire, England, have invented and produced a new, original, and ornamental Design for a Cup, of which the following is a specification, reference being had to the accompanying drawings, forming a part thereof, in which—

10 Figure 1 is a perspective view of a cup embodying the features of my design, and Fig. 2 is a bottom plan view of the same.

The design consists in the following exterior formation and decorations: The upper 15 portion of the cup is plain and cylindrical; but that portion adjacent and leading to the bottom flange is vertically fluted, the depressions producing the fluted effect being pronounced at the bottom portion of the body, 20 but gradually merge into the said plain up-

per surface. The handle is a ring-handle in the form of a continuous stem and is at one side of the body of the cup. At the bottom of each alternate pair of knuckles or projections on the body formed by the aforesaid depressions leaf decorations appear, the leaves being placed stem to stem, and between each group of leaves a bar-scroll is introduced.

Having thus described my invention, I claim as new and desire to secure by Letters 25 Patent—

The ornamental design for a cup herein shown and described.

In testimony whereof I have signed my name to this specification in the presence of 30 two subscribing witnesses.

ROBERT L. JOHNSON.
